DUSTING MACHINE

Robert J. Geary, Blue Point, N. Y.

Application July 13, 1956, Serial No. 42,246

Term of patent 14 years

(Cl. D31—3)

FIG. 3

FIG. 4

Fig. 1 is a side elevational view of a dusting machine showing my new design;

Fig. 2 is a top plan view thereof;

Fig. 3 is a front elevational view; and

Fig. 4 is a rear elevational view thereof.

The broken away portions represent indefinite length.

I claim:

The ornamental design for a dusting machine, substantially as shown and described.
